A. J. E. RYLANDER

MEANS FOR CONTROLLING AND REVERSING VESSELS

Filed Sept. 24, 1924

Inventor
F. J. C. Rylander

UNITED STATES PATENT OFFICE.

ANDERS JOHAN EMIL RYLANDER, OF STOCKHOLM, SWEDEN.

MEANS FOR CONTROLLING AND REVERSING VESSELS.

Application filed September 24, 1924, Serial No. 739,602, and in Sweden October 24, 1923.

This invention has for its object improvements in such controlling and reversing means for propeller-driven vessels that consists of a number of plates behind the propeller, normally folded together to form a common rudder, but that upon changing of the speed or reversing of the vessel are unfolded, so as to form an obstacle to the current from the propeller and wholly or partly force the water current to deflect and return, thus causing the vessel to reverse or change its speed without at the same time reversing or changing the speed of the motive power agent; and the objects of my improvements are to provide such a construction that the heavy resistance caused by the pressure of the water upon the rudder plates at the opening or closing of the rudder is eliminated as nearly as possible; at the same time providing an uncomplicated mechanism for the opening and closing of the rudder; and a rudder that in its normally closed position will be of such a shape as not to lower the normal speed of the vessel.

In the accompanying drawing illustrating by way of example the present invention—

Fig. 1 shows a side elevation of a reversing rudder in normal or closed position;

Fig. 2 shows the same in plan view seen from above;

Fig. 3 is a section of the rudder on the line A—A of Fig. 1;

Fig. 4 shows the rudder in plan in fully expanded position; and

Fig. 5 in plan in partly expanded position.

Similar numerals refer to the same parts throughout the several views.

The reversing rudder, which is to be attached to the stern portion of the hull of a vessel in the usual way, comprises two vertical rudder plates or steering plates 1 and 2, the upper and lower edges of which are bent, abutting against each other, when the rudder is collapsed, so that a space is enclosed by the plates. The plates 1 and 2 are hingedly connected to triangular plates, i. e. at the top to the plates 3 and 4 and at the bottom to the plates 5 and 6 respectively. When the rudder is collapsed the triangular

plates are housed in the space between the rudder plates 1 and 2, the upper plates with their point directed in downward direction and the lower plates with their point upwards, (see Fig. 1). The hinged connection between the triangular plates and the rudder

plates may be of any suitable kind. As shown on the drawing, the triangular plates may be provided along one of their edges with two or more projections 29, entering corresponding openings in the rudder plates 60 and locked to the latter on their outside.

The two triangular plates 3 and 4 are connected by a universal joint 13, 14 (see Figs. 4 and 5), and the plates 5 and 6 are in the same way connected by a universal joint. 65 The points of the triangular plates are cut away to provide space for the universal joints.

11 and 12 are two coaxial rudder shafts of which 12 is hollow and encloses the upper 70 part of the solid shaft 11.

Along a vertical line through the centre of gravity or its neighbourhood the rudder plates 1 and 2 are pivotally connected by means of a journal pin 9 and 10 respectively 75 with an arm or lever 7 and 8 respectively, which are rigidly connected, the arm 7 to the hollow shaft 12 and the arm 8 to the shaft 11. The arms 7 and 8 are each provided with a stop 28 and 27 respectively. 30 is a 80 sleeve placed around the shaft 11 in the prolongation of the hollow shaft 12, to form a support against the sole piece.

Astern of their centres of gravity the rudder plates are connected by hinged links 85 17 and 18, each of the latter pivoting in bearings 31 and 32, attached to the plates. The links 17 and 18 are pivotally connected by a suitable device 33. When the rudder is closed, the links lie collapsed backwards (see 90 Fig. 1) in the chamber between the rudder plates, while in the reversing position they are fully stretched between the rudder plates in the oblique position the latter then occupy (see Fig. 4), keeping their rear edges close 95 against each other. To prevent the links from turning forward in the closing action of the rudder the ends 34, 35 of the links are bent over.

Rigidly attached to each of the rudder 100 shafts 11 and 12 at the top are respectively toothed sectors 19 and 20 in mesh with spur gears 21 and 22 respectively, each rigidly connected to a chain wheel or the like 23 and 24. Arranged between the toothed sectors 19, 20 and the spur gears 21, 22 is a bar 25, one end of which loosely embraces the rudder shaft 11, while the opposite end is attached to some part of the hull of the vessel in any suitable way (not shown). At 110

a suitable distance from the shaft 11 the bar 25 supports a journal pin 26 about which the spur gears 21 and 22 are adapted to rotate.

- 5 If the chain wheels 23 and 24, and with them the shafts 11 and 12, are rotated in the same direction, both of the rudder plates 1 and 2 will be turned in the same direction. The rudder will thus remain closed and will 10 act like a common rudder. If, however, the chain wheels and with them the shafts 11 and 12 are rotated in opposite directions, the arms 7 and 8 will also be rotated in opposite directions and by this action will cause 15 the rudder plates 1 and 2 to move apart thus opening the rudder. On account of the journal pins 9 and 10 being freely rotatable in the end-bearings of the arms 7 and 8, the rudder plates at the beginning of the 20 opening of the rudder will be free to swing about their hinge pins, and thus will automatically assume the positions, in which they offer the least resistance to the movements, that is parallel with the water current 25 coming from the propeller (Fig. 5). The chain wheels 23 and 24 can be made to turn simultaneously equally in opposite direction, and equally in the same direction, by means of a suitable transmission mechanism, 30 for instance of the kinds described and illustrated in my U. S. Patent No. 1,526,238 (Figs. 9 and 10).

In the opening action of the rudder the collapsed links 17 and 18 commence to spread 35 out, finally occupying the fully extended position shown in Fig. 5, the plates 1 and 2 however being still parallel to each other and to the water current. Simultaneously with these movements, the triangular plates 3, 4 and 5, 6, held together by the universal joints 13, 14, are turned about their hinges and more and more extended. During the 40 continued rotation of the arms 7 and 8 the bearings 31 and 32 are moved forward along two parallel lines, on account of the links 17 and 18 being extended, thus preventing further lateral motion of these bearings. At 45 the same time, however, the journal pins 9, 10 are moving along circular lines with the rudder-shafts as centre. The rudder plates 1, 2 accordingly perform a double rotary motion and occupy a more and more oblique position, until finally their rear edges come 50 in contact with each other, the rudder then being fully expanded as shown in Fig. 4.

During the spreading movement from the position in Fig. 5 to the position in Fig. 4, the water current will press upon the steering plates on both sides of the journal pins 9 and 10 with forces of which the moments counteract each other. For this reason the journal pins should be given such positions that the moments of these forces as nearly as possible neutralize each other. 60 The steering plates will then be perfectly

balanced in all positions and a very small force will be required for the opening or closing of the rudder.

In the final position (Fig. 4) the triangular plates 3, 4 and 5, 6 are completely extended, and occupy horizontal positions at the top and bottom of the steering plates with two of their edges abutting against each other. By the triangular plates the water current is prevented from making its 70 way upwards or downwards, but is forced to turn in the expanded rudder by the rudder plates 1, 2 and to move sidewise to forward, driving the vessel back. The triangular plates are held in their position and supported by the stops 28 and 27, attached to the arms 7 and 8. During the back drive the vessel is steered by rotating the wheels 23 and 24 in the same direction. 75

The invention is capable of various 80 changes as to details of construction and the right is herein reserved to make such changes as properly fall within the scope of the appended claims.

What I claim is:—

1. A reversing rudder for propeller-driven vessels consisting of a rudder trunk comprising two rotatable shafts; a pair of vertical rudder plates normally folded together forming a common rudder; arms or levers 90 rigidly attached to the rudder trunk and pivotally connected to the rudder plates; means for expanding the rudder plates; and means for approaching the rear edges of the expanded rudder plates against each other. 95

2. A reversing rudder for propeller-driven vessels consisting of a rudder trunk comprising two rotatable shafts; a pair of vertical rudder plates normally folded together forming a common rudder; arms or levers supporting the rudder plates; said arms or levers being rigidly attached to the rudder trunk and pivotally connected to the rudder plates; means for expanding the rudder plates; and means for approaching the rear edges of the expanded rudder plates against each other. 105

3. A reversing rudder for propeller-driven vessels consisting of a rudder trunk comprising two rotatable shafts; a pair of vertical rudder plates normally folded together forming a common rudder; means for expanding the rudder plates; means for approaching the rear edges of the expanded rudder plates against each other; and means 115 for supporting the rudder plates in a way to allow them to swing freely about their supports at the beginning of the opening action.

4. A reversing rudder for propeller-driven vessels consisting of a rudder trunk comprising two rotatable shafts; a pair of vertical rudder plates normally folded together forming a common rudder; arms or levers rigidly attached to the rudder trunk 125

and pivotally connected to the rudder plates in a way to allow the latter to swing freely about the pivots at the beginning of the opening action of the rudder; means for expanding the rudder plates; and means for approaching the rear edges of the expanded rudder plates against each other.

5. A reversing rudder for propeller-driven vessels consisting of a rudder trunk comprising two rotatable shafts; a pair of vertical rudder plates normally folded together forming a common rudder; arms or levers rigidly attached to the rudder trunk and supporting the rudder plates in a way to allow the latter to swing freely about these supports at the beginning of the opening action of the rudder plates; means for expanding the rudder plates; and means for approaching the rear edges of the expanded rudder plates against each other.

6. A reversing rudder for propeller-driven vessels consisting of a rudder trunk comprising two rotatable shafts; a pair of vertical rudder plates normally folded together forming a common rudder; vertical journal pins attached to the rudder plates; arms or levers rigidly attached to the rudder trunk and pivotally connected to the rudder plates by means of the said journal pins; means for expanding the rudder plates; and means for approaching the rear edges of the expanded rudder plates against each other.

7. A reversing rudder for propeller-driven vessels consisting of a rudder trunk comprising two rotatable shafts; a pair of vertical rudder plates normally folded together forming a common rudder; vertical journal pins attached to the rudder plates; arms or levers supporting the rudder plates; said arms or levers being rigidly attached to the rudder trunk and pivotally connected to the rudder plates by means of the said journal pins; means for expanding the rudder plates; and means for approaching the rear edges of the expanded rudder plates against each other.

8. A reversing rudder for propeller-driven vessels consisting of a rudder trunk comprising two rotatable shafts; a pair of vertical rudder plates normally folded together forming a common rudder; arms or levers rigidly attached to the rudder trunk and pivotally connected to the rudder plates at or in the neighbourhood of the point of gravity of the latter; means for expanding the rudder plates; and means for approaching the rear edges of the expanded rudder plates against each other.

9. A reversing rudder for propeller-driven vessels consisting of a rudder trunk comprising two rotatable shafts; a pair of vertical rudder plates normally folded together forming a common rudder; vertical journal pins attached to the rudder plates at or in the neighbourhood of the point of

gravity of the latter; arms or levers rigidly attached to the rudder trunk and pivotally connected to the rudder plates by means of the said journal pins; means for expanding the rudder plates; and means for approaching the rear edges of the expanded rudder plates against each other.

10. A reversing rudder for propeller-driven vessels consisting of a rudder trunk comprising two rotatable shafts; a pair of vertical rudder plates normally folded together forming a common rudder; vertical journal pins attached to the rudder plates at or in the neighbourhood of the point of gravity of the latter; arms or levers supporting the rudder plates; said arms or levers being rigidly attached to the rudder trunk and pivotally connected to the rudder plates by means of the said journal pins; means for expanding the rudder plates; and means for approaching the rear edges of the expanded rudder plates against each other.

11. A reversing rudder for propeller-driven vessels consisting of two coaxially arranged rotatable shafts; a pair of vertical rudder plates normally folded together forming a common rudder; arms or levers rigidly attached to the said shafts and pivotally connected to the rudder plates; means for expanding the rudder plates; and means for approaching the rear edges of the expanded rudder plates against each other.

12. A reversing rudder for propeller-driven vessels consisting of two coaxially arranged rotatable shafts; a pair of vertical rudder plates normally folded together forming a common rudder; arms or levers supporting the rudder plates; said arms or levers being rigidly attached to the said shafts and pivotally connected to the rudder plates; means for expanding the rudder plates; and means for approaching the rear edges of the expanded rudder plates against each other.

13. A reversing rudder for propeller-driven vessels consisting of two coaxially arranged rotatable shafts; a pair of vertical rudder plates normally folded together forming a common rudder; means for expanding the rudder plates; means for approaching the rear edges of the expanded rudder plates against each other; and means for supporting the rudder plates in a way to allow them to swing freely about their supports at the beginning of the opening action.

14. A reversing rudder for propeller-driven vessels consisting of two coaxially arranged rotatable shafts; a pair of vertical rudder plates normally folded together forming a common rudder; arms or levers rigidly attached to the said shafts and pivotally connected to the rudder plates; means for expanding the rudder plates; means for

approaching the rear edges of the expanded rudder plates against each other; and means for supporting the rudder plates in a way to allow them to swing freely about their supports at the beginning of the opening action.

15. A reversing rudder for propeller-driven vessels consisting of two coaxially arranged rotatable shafts; a pair of vertical rudder plates normally folded together forming a common rudder; arms or levers rigidly attached to the said shafts and pivotally connected to the rudder plates in a way to allow the latter to swing freely about the pivots at the beginning of the opening action of the rudder; means for expanding the rudder plates; and means for approaching the rear edges of the expanded rudder plates against each other.

16. A reversing rudder for propeller-driven vessels consisting of two coaxially arranged rotatable shafts; a pair of vertical rudder plates normally folded together forming a common rudder; arms or levers rigidly attached to the said shafts and supporting the rudder plates in a way to allow the latter to swing freely about these supports at the beginning of the opening action of the rudder plates; means for expanding the rudder plates; and means for approaching the rear edges of the expanded rudder plates against each other.

17. A reversing rudder for propeller-driven vessels consisting of two coaxially arranged rotatable shafts; a pair of vertical rudder plates normally folded together forming a common rudder; vertical journal pins attached to the rudder plates; arms or levers rigidly attached to the said shafts and pivotally connected to the rudder plates by means of the said journal pins; means for expanding the rudder plates; and means for approaching the rear edges of the expanded rudder plates against each other.

18. A reversing rudder for propeller-driven vessels consisting of two coaxially arranged rotatable shafts; a pair of vertical rudder plates normally folded together forming a common rudder; vertical journal pins attached to the rudder plates; arms or levers supporting the rudder plates; said arms or levers being rigidly attached to the said shafts and pivotally connected to the rudder plates by means of the said journal pins; means for expanding the rudder plates; and means for approaching the rear edges of the expanded rudder plates against each other.

19. A reversing rudder for propeller-driven vessels consisting of two coaxially arranged rotatable shafts; a pair of vertical rudder plates normally folded together forming a common rudder; arms or levers rigidly attached to the said shafts and pivotally connected to the rudder plates at or

in the neighbourhood of the point of gravity of the latter; means for expanding the rudder plates; means for approaching the rear edges of the expanded rudder plates against each other.

20. A reversing rudder for propeller-driven vessels consisting of two coaxially arranged rotatable shafts; a pair of vertical rudder plates normally folded together forming a common rudder; vertical journal pins attached to the rudder plates at or in the neighbourhood of the point of gravity of the latter; arms or levers rigidly attached to the said shafts and pivotally connected to the rudder plates by means of the said journal pins; means for expanding the rudder plates; and means for approaching the rear edges of the expanded rudder plates against each other.

21. A reversing rudder for propeller-driven vessels consisting of a rudder trunk comprising two rotatable shafts; a pair of vertical rudder plates normally folded together forming a common rudder; arms or levers rigidly attached to the rudder trunk and pivotally connected to the rudder plates; means for expanding the rudder plates; and means for approaching the rear edges of the expanded rudder plates against each other, consisting of a system of collapsible links pivotally connected to the rudder plates astern of their centres of gravity.

22. A reversing rudder for propeller-driven vessels consisting of a rudder trunk comprising two rotatable shafts; a pair of vertical rudder plates normally folded together forming a common rudder; arms or levers supporting the rudder plates; said arms or levers being rigidly attached to the rudder trunk and pivotally connected to the rudder plates; means for expanding the rudder plates; and means for approaching the rear edges of the expanded rudder plates against each other, consisting of a system of collapsible links pivotally connected to the rudder plates astern of their centres of gravity.

23. A reversing rudder for propeller-driven vessels consisting of a rudder trunk comprising two rotatable shafts; a pair of vertical rudder plates normally folded together forming a common rudder; means for supporting the rudder plates in a way to allow them to swing freely about their supports at the beginning of the opening action; means for expanding the rudder plates; and means for approaching the rear edges of the expanded rudder plates against each other; consisting of a system of collapsible links pivotally connected to the rudder plates astern of their centres of gravity.

24. A reversing rudder for propeller-driven vessels consisting of a rudder trunk comprising two rotatable shafts; a pair of vertical rudder plates normally folded to-

- gether forming a common rudder; arms or levers rigidly attached to the rudder trunk and pivotally connected to the rudder plates; means for supporting the rudder plates in a way to allow them to swing freely about their supports at the beginning of the opening action; means for expanding the rudder plates; and means for approaching the rear edges of the expanded rudder plates against each other; consisting of a system of collapsible links pivotally connected to the rudder plates astern of their centres of gravity. 70
25. A reversing rudder for propeller-driven vessels consisting of a rudder trunk comprising two rotatable shafts; a pair of vertical rudder plates normally folded together forming a common rudder; arms or levers rigidly attached to the rudder trunk and pivotally connected to the rudder plates in a way to allow the latter to swing freely about the pivots at the beginning of the opening action of the rudder; means for expanding the rudder plates; and means for approaching the rear edges of the expanded rudder plates against each other consisting of a system of collapsible links pivotally connected to the rudder plates astern of their centres of gravity. 75
26. A reversing rudder for propeller-driven vessels consisting of a rudder trunk comprising two rotatable shafts; a pair of vertical rudder plates normally folded together forming a common rudder; arms or levers rigidly attached to the rudder trunk and supporting the rudder plates in a way to allow the latter to swing freely about these supports at the beginning of the opening action of the rudder plates; means for expanding the rudder plates; and means for approaching the rear edges of the expanded rudder plates against each other consisting of a system of collapsible links pivotally connected to the rudder plates astern of their centres of gravity. 80
27. A reversing rudder for propeller-driven vessels consisting of a rudder trunk comprising two rotatable shafts; a pair of vertical rudder plates normally folded together forming a common rudder; vertical journal pins attached to the rudder plates; arms or levers rigidly attached to the rudder trunk and pivotally connected to the rudder plates by means of the said journal pins; means for expanding the rudder plates; and means for approaching the rear edges of the expanded rudder plates against each other, consisting of a system of collapsible links pivotally connected to the rudder plates astern of their centres of gravity. 85
28. A reversing rudder for propeller-driven vessels consisting of a rudder trunk comprising two rotatable shafts; a pair of vertical rudder plates normally folded together forming a common rudder; vertical journal pins attached to the rudder plates; said arms or levers supporting the rudder plates; said arms or levers being rigidly attached to the rudder trunk and pivotally connected to the rudder plates by means of the said journal pins; means for expanding the rudder plates, and means for approaching the rear edges of the expanded rudder plates against each other; consisting of a system of collapsible links pivotally connected to the rudder plates astern of their centres of gravity. 90
29. A reversing rudder for propeller-driven vessels consisting of a rudder trunk comprising two rotatable shafts; a pair of vertical rudder plates normally folded together forming a common rudder; arms or levers rigidly attached to the rudder trunk and pivotally connected to the rudder plates at or in the neighbourhood of the point of gravity of the latter; means for expanding the rudder plates; and means for approaching the rear edges of the expanded rudder plates against each other consisting of a system of collapsible links pivotally connected to the rudder plates astern of their centres of gravity. 95
30. A reversing rudder for propeller-driven vessels consisting of a rudder trunk comprising two rotatable shafts; a pair of vertical rudder plates normally folded together forming a common rudder; vertical journal pins attached to the rudder plates at or in the neighbourhood of the point of gravity of the latter; arms or levers rigidly attached to the rudder trunk and pivotally connected to the rudder plates by means of the said journal pins; means for expanding the rudder plates; and means for approaching the rear edges of the expanded rudder plates against each other, consisting of a system of collapsible links pivotally connected to the rudder plates astern of their centres of gravity. 100
31. A reversing rudder for propeller-driven vessels consisting of a rudder trunk comprising two rotatable shafts; a pair of vertical rudder plates normally folded together forming a common rudder; vertical journal pins attached to the rudder plates at or in the neighbourhood of the point of gravity of the latter; arms or levers supporting the rudder plates; said arms or levers being rigidly attached to the rudder trunk and pivotally connected to the rudder plates by means of the said journal pins; means for expanding the rudder plates, and means for approaching the rear edges of the expanded rudder plates against each other; consisting of a system of collapsible links pivotally connected to the rudder plates astern of their centres of gravity. 105
32. A reversing rudder as set forth in claim 1; and provided with a pair of triangular plates hinged to the top of the rudder plates; and a pair of similar plates hinged to the bottom of the rudder plates; said tri- 110
- 115

- 125
- 130

angular plates being adapted to be normally folded together in pairs between the rudder plates.

33. A reversing rudder as set forth in claim 1; and provided with a pair of triangular plates hinged to the top of the rudder plates; and a pair of triangular plates hinged to the bottom of the rudder plates; said triangular plates being in pairs connected by universal joints and normally folded together between the rudder plates.

34. A reversing rudder as set forth in claim 1; and provided with a pair of triangular plates hinged to the top of the rudder plates; and a pair of triangular plates hinged to the bottom of the rudder plates; said plates being normally folded together in pairs between the rudder plates; means for unfolding of the said triangular plates at the opening action of the rudder so as to

form deflectors at the top and bottom of the space confined between the expanded rudder; stops being provided to retain and support the triangular plates in their unfolded position.

35. A reversing rudder as set forth in claim 1; and provided with a pair of triangular plates provided with a number of projections engaging in corresponding openings at the top of the rudder plates and locked to the latter on their outside so as to form a hinged connection; and a pair of triangular plates hinged in the same way to the bottom of the rudder plates; the said triangular plates being normally folded together in pairs between the rudder plates.

In witness whereof I have hereunto set my hand.

ANDERS JOHAN EMIL RYLANDER.
